UNITED STATES PATENT OFFICE

WILLIAM F. HELMOND, OF HARTFORD, CONNECTICUT, ASSIGNOR TO UNDERWOOD WRITER COMPANY, OF NEW YORK, N. Y., A CORPORATION OF NEW JERSEY.

TYPE-WRITING MACHINE.

No. 890,358.

Specification of Letters Patent.

Patented June 9, 1908

Application filed October 21, 1907. Serial No. 398,306.

To all whom it may concern:

Be it known that I, WILLIAM F. HELMOND, a citizen of the United States, residing in Hartford, in the county of Hartford and State of Connecticut, have invented certain new and useful Improvements in Type-Writing Machines, of which the following is a specification.

This invention relates to paper feeding and guiding devices of typewriting machines, and particularly to means for controlling the pressure rolls that run upon the usual cylindrical platen.

The object of the invention is to provide simplified, inexpensive and effective means for feeding and guiding the paper around the platen, and also for holding the paper firmly against the platen; also to means for releasing the rolls and holding them released or locked away from the platen during the introduction and adjustment of the paper sheets.

In the accompanying drawings, Figure 1 is a front view of a platen frame of an Underwood front strike writing machine. Fig. 2 is a perspective view illustrating the mounting of the rolls and the releasable means therefor. Fig. 3 is an end view of the paper feeding and guiding devices, showing the pressure rolls released and locked away from the platen. Fig. 4 is a view similar to Fig. 3, but showing the releasable means in normal position.

In machines of the class referred to the types usually strike upon the front side of the platen 1, which is revolvably mounted by means of an axle 2 in the ends 3 of a platen frame. A rod 4 is rigidly fixed in the platen-frame ends and lies below and parallel with the platen. Sets of front and rear pressure rolls 5, 6 are carried upon shafts 7, 8, said shafts resting in cradles or yokes 9. Each of the latter has a U-shaped yoke portion and arms 10, 11 extending forwardly and rearwardly therefrom, said arms having open bearings 12, 13, to receive said roll-shafts and permit detachment thereof. Hangers or bearing-blocks 14 are secured to the rod 4, in which is journaled a rock-shaft 15, having cams 16 formed thereon. The rock-shaft is connected by means of a link 17 to a key 18 pivoted upon the platen frame. Springs 19, 20 secured to the hangers 14 extend inwardly from the end of the platen, and are bent up at their free ends, as at 21, to engage cam portions 16 on the rock-shaft 15. Collars 22, 23,

also fixed upon the rod 4 guide the yokes 9, and serve as bearings for the rock-shaft 15.

The springs 19, 20 normally exert upward pressure on the yokes 9, and press the rolls 5, 6 against the platen. At this time the ends or tips 21 of the springs are out of engagement with the cam portion 16 of shaft 15. By depressing the release key 18 to the Fig. 3 position, the link 17 is caused to pull up a crank 25 provided upon the rock-shaft 15, and rocks the latter, which cams down the springs 19, 20 and locks them out of engagement with the yokes 9. The latter drop and release the rolls from the platen. The operator may now readily adjust the paper, and after such adjustment raise the finger piece 18, thereby unlocking the springs and restoring the rolls to normal condition, Fig. 4.

Having thus described my invention, I claim:

1. In a typewriting machine, the combination with a revoluble platen and pressure rolls running thereon and divided into front and rear sets, each set having an axle, of a yoke guided upon the platen frame for movement towards and away from the platen, and having open slots to engage said axles to guide all of said rollers, and releasable means for pressing the rollers against the platen; said axles being detachable from said yoke.

2. In a typewriting machine, the combination with a revoluble platen and pressure rolls running thereon and divided into front and rear sets, each set having an axle, of yokes having slots to engage rods extending along said platen frame, to guide the yokes for movement towards and away from the platen, said yokes having means to engage said axles to press and guide all of said rollers, and releasable means for pressing the yokes towards the platen.

3. In a typewriting machine, the combination with a platen and a plurality of pressure rollers, of a key-operated rock-shaft provided with a cam, a spring, and means for enabling said spring to press said rollers against the platen; said spring having a part to engage said cam to be depressed thereby to roller-releasing position.

4. In a typewriting machine, the combination with a platen and a set of pressure rollers, of a key-operated rock-shaft extending along the platen and provided with cams, spring fingers mounted upon the platen frame and extending along the platen, the

tips of said fingers being engageable by said cams, and devices actuated by said springs to press the rolls against the platen; said springs being releasable by the action of said cams thereon during the rocking of said shaft.

5. In a typewriting machine, the combination with a platen and a set of pressure rollers, of spring fingers mounted upon the 10 platen frame and extending along the platen, yokes engageable by said spring fingers and extending to the rollers to press the latter against the platen, tips provided upon the ends of said fingers, the latter extending past 15 said yokes, and a key-operated shaft extending along the platen and provided with cams to engage said tips to release said springs and lock them in ineffective positions.

6. In a typewriting machine, the combination with a platen frame and a platen, of two sets of rollers running upon the platen, two shafts upon which said rollers are mounted, yokes having oppositely-extending arms in 20 which said shafts are journaled, a spring engaging each yoke and pressing the rollers against the platen, and means for throwing and locking the springs out of engagement 25 with the yokes.

7. In a typewriting machine, the combination with a platen frame and a platen, of rollers running upon the platen and shafts upon which said rollers are mounted, yokes having oppositely-extending arms in which the roller shafts are journaled, springs engaging with the yokes and pressing the rollers against the platen, and a rock-shaft having means to throw the springs out of engagement with the yokes.

8. In a typewriting machine, the combination with a platen frame and a platen, of sets of rollers running upon the platen, shafts upon which said rollers are mounted, a plurality of yokes having oppositely-extending arms in which the roller-shafts are journaled, 40 springs engaging the yokes and pressing the rollers against the platen, and a key-operated rock-shaft having cams thereon to throw and lock said springs out of engagement with the yokes.

9. In a typewriting machine provided with a platen and a platen frame, the combination of two sets of rollers running upon the platen, two shafts upon which said rollers are mounted, a plurality of yokes having 55 oppositely-disposed arms in which the roller-shafts are journaled, springs engaging the yokes to press the rollers against the platen, and a rock-shaft having cams thereon connected with a key and operable to throw said springs out of engagement with the yokes and thereby releasing the pressure on the rollers.

10. In a typewriting machine provided with a platen and a platen frame, the combination with a pair of shafts and a set of roll-

ers mounted upon each shaft, of a rod lying between said roller-shafts and having a bearing block at each end, a rock-shaft mounted in said blocks and connected to a lever, cams on said rock-shaft, a plurality of yokes having oppositely-disposed arms in which the roller-shafts are journaled, and springs engaging said yokes and pressing the roller-shafts and rollers against the platen, said springs being movable by the cams on the 70 rock-shaft to release the pressure on the rollers.

11. In a typewriting machine, the combination with a platen and a platen frame, of two sets of rollers running upon the platen, 80 shafts upon which said rollers are mounted, a rod mounted in the ends of the platen frame and lying between the roller-shafts, a rock-shaft having a cam thereon journaled in hangers secured to the rod, a lever connected to said rock-shaft, a yoke bestriding the rock-shaft and having oppositely-extending arms in which the roller shafts are journaled, a leaf spring at one end secured to one of the hangers and normally bearing with its free 85 end against the yoke; said free end of the spring also being engaged by the cam on the rock-shaft to release the pressure on the yoke.

12. In a typewriting machine, the combination with a platen and a platen frame, of two sets of rollers, shafts upon which said rollers are mounted, a rock-shaft having cams thereon and connected to a lever, yokes in which the roller-shafts are journaled, and a leaf spring normally pressing against each 95 yoke, said spring being movable by a cam on the rock-shaft to release the pressure on the yokes.

13. In a typewriting machine provided 100 with a platen and a platen frame, the combination with a pair of shafts and a set of rollers mounted upon each shaft, of a rod mounted in the platen-frame ends so as to lie between said roller-shafts, a pair of bearing blocks or hangers mounted on said rod, a rock-shaft journaled in said blocks and having a link and lever connection, cams on said 110 rock-shaft, a plurality of yokes bestriding said rock-shaft and having oppositely-extending arms in which the roller-shafts are journaled, and leaf springs secured to the underside of each of said blocks and bearing against said yokes and thereby pressing the rollers against the platen, said springs being 120 movable by the cams on the rock-shaft to lock said springs out of engagement with, and to release the pressure on, the yokes.

14. In a typewriting machine provided 125 with a platen and a platen frame, the combination with two sets of rollers running upon the platen, and shafts upon which said rollers are mounted, of a rod mounted in the ends of the platen frame and lying between the roller-shafts, a rock-shaft having cams 130

thereon journaled in hangers secured to the rod, a lever connected to said rock-shaft, yokes bestriding the rock-shaft and having oppositely-extending arms in which the roller shafts are journaled, and a pair of springs one secured to each of the hangers at one end and its other end engaging a cam on the rock-shaft, said spring bearing against the yokes and thereby pressing the rollers against the 10 platen, and movable by the cams on the rock-shaft to throw the same out of engagement with, and to release the pressure on, the yokes.

15. In a typewriting machine provided with a platen and a platen frame, the combination with two sets of rollers running upon the platen, shafts upon which said rollers are mounted, and a rod mounted in the ends of the platen frame and lying between the roller

shafts, of a rock-shaft having cams thereon journaled in hangers secured to the rod, a lever connected to said rock-shafts, yokes bestriding the rock-shaft and having oppositely-extending arms in which the roller shafts are journaled, and a pair of springs, each spring 20 connected at one of its ends to the under side of one of the hangers and the free ends of the springs bent up at a substantially right angle and engaging cams on the rock-shaft, said springs normally bearing against the yokes 25 and thereby pressing the rollers against the platen, and movable by the cams on the rock-shaft to lock the same in roller-releasing positions.
